HOUSE BOAT OR SIMILAR ARTICLE

George W. Meek, Fort Myers, Fla., assignor to General Panel Corporation, Fort Myers, Fla., a corporation of New York

Filed June 10, 1960, Ser. No. 60,911

Term of patent 7 years

(Cl. D71—1)

FIG. 1 is a side elevation of a house boat or similar article embodying my new design;

FIG. 2 is an end elevation of the same, and

FIG. 3 is an elevation of the end opposite to that shown in FIG. 2.

The top is plain except for the railing as shown in FIGURES 1, 2 and 3, and the side not shown is substantially the same as that of FIGURE 1.

I claim:

The ornamental design for a house boat or similar article, substantially as shown and described.
